ATTORNEYS

UNITED STATES PATENT OFFICE.

JOSEPH BOLLER, OF BROOKLYN, NEW YORK.

DESIGN FOR A BAT.

SPECIFICATION forming part of Design No. 24,641, dated August 27, 1895.

Application filed July 12, 1895. Serial No. 555,774. Term of patent 7 years.

To all whom it may concern:

Be it known that I, JOSEPH BOLLER, a subject of the Emperor of Germany, residing at Brooklyn, Kings county, State of New York, have invented and produced a new and original Design for Bats, of which the following is a specification.

The leading feature of my design is a bat of essentially the configuration and representation shown in the accompanying drawing, which represents a bat embodying my design.

In the drawing, A is the body portion of the bat of a curvilinear form, substantially as shown, from whose edges project a series of

globular ornaments $aa' a''$. The body portion 15 is crossed by lines b , and is contracted or narrowed at its lower end B. From the contracted portion extends a handle or elongated projection D, which terminates in a bulbous ornament d.

What I claim is—

The design for a bat, substantially as herein shown and described.

JOSEPH BOLLER.
